UNITED STATES PATENT OFFICE.

JOHN W. MCPHERSON, OF MOLINE, ILLINOIS.

BRAKE-LEVER.

SPECIFICATION forming part of Letters Patent No. 379,969, dated March 27, 1888.

Application filed September 8, 1887. Serial No. 249,072. (No model.)

To all whom it may concern:

Be it known that I, JOHN W. MCPHERSON, a citizen of the United States, residing at Moline, in the county of Rock Island and State 5 of Illinois, have invented a new and useful Lever for Manipulating the Draw-Rod of a Wagon-Brake, of which the following is a specification.

My invention relates to improvements in 10 levers for forcing the shoe of a wagon-brake through its draw-rod against the face of the tire of the wagon-wheel, and the objects are, first, to acquire the greatest leverage from the lever-arm when the shoe is against the tire of 15 the wheel—that is, when the lever-arm is thrown forward and is moving near the farthest extent permitted; second, to arrange the pawl with a projection and the arc of the plate forward of its teeth somewhat on a tangent, or 20 not a true circle, so that as the pawl passes forward of the teeth such portion of the arc will so guide the front end of the pawl as to cause its projection to bind or lock against the connected parallel short arm of the lever-arm 25 to prevent the device from rattling and the lever-arm from lateral or other movement; and, third, to so connect the finger elbow-lever upon the lever-arm and the pawl, so that the projection on the pawl, coming in contact 30 with the connected parallel short arm of the lever-arm, will limit the movement of the finger elbow-lever so as to prevent pinching the fingers or hand of the operator when operating the same. I attain these objects by the 35 mechanism illustrated in the accompanying drawings, in which—

Figure 1 is a front view of my device as it appears when attached to the side of a wagon-box. Fig. 2 is a front or plan view of the 40 plate. Fig. 3 is a top view of the same. Fig. 4 is a front or plan view of arm E, and Fig. 5 is a top view of the same.

Similar letters refer to similar parts throughout the several views.

45 A represents the plate, segmental in form, or having an arc, which plate is attached to the side of a wagon-box by the bolts and nuts a and b; and c represents teeth or notches upon the arc of said plate.

50 I construct the plate so it may project out-

wardly from the wagon-box and leave an open space between its inner surface and the wagon-box by curving the two extreme ends of the plate inward, so as to form legs terminating in feet, with holes through which bolts a and b pass to 55 secure the plate to the side of the wagon-box. Midway upon a line substantially the chord of the arc of said plate I pivot the lever-arm B to said plate by the bolt d, which lever-arm extends both above and below said pivotal 60 point d. On the outer side of plate A, I also pivot on bolt d a short parallel arm, C, which extends substantially the same distance below said pivotal point as does lever-arm B, but, however, said lever-arm B is pivoted on the 65 inner side of plate A. Just below the arc of plate A, I pivot, between lever-arm B and parallel short arm C, the pawl D, so that its front end may engage with the teeth or notches c, its other end being sufficiently heavy or 70 weighted to automatically raise the other end and keep it in engagement with said teeth or notches c. Near the upper end of lever-arm B is pivoted a finger elbow-lever, e, to the short arm of which elbow-lever is attached the 75 upper end of connecting-rod f, which passes down along lever-arm B, and its lower end is attached to the heavy or weighted part of pawl D.

The handle or upper part of finger elbow- 80 lever e, when pulled toward lever-arm B by the operator, disengages pawl D from the notches or teeth c. A projection, g, on pawl D limits its movement by coming in contact with the short parallel arm C, and through 85 connecting-rod f also limits the movement of the upper part of finger elbow-lever e toward lever-arm B, so that the fingers and hand of the operator cannot be pinched when manipulating the lever-arm and pawl. 90

The arc of plate A, forward of the teeth or notches c, is not continued in a true circle, but extends forward somewhat in a tangent at c', so that when the forward end of pawl D passes forward of said teeth or notches c it 95 moves against this tangent part of the arc, which elevates the opposite end of pawl D, so that its projection g comes in contact and binds tightly against the short arm C, whereby the lever-arm B is prevented from moving laterally 100

or otherwise, and avoiding the noise incident to levers of this class from the movement of the wagon when the wagon-brake is not set.

The arm E at its lower end has the perforations *h* and *i*, through one of which, as desired, the bolt *a* passes, secured by a nut; but I do not limit myself to these, as one or more perforations may be made. The upper part of arm E is bent or turned, having a longitudinal slot cut through it, as at *j*, at the front end of which slot is inserted the roller K upon proper bearings. At the upper part of said arm E, near the bend or turn, are perforations *l* and *m*; but I do not limit myself to these, as one or more perforations may be made.

The lever-arm B, above its pivotal point *d*, is inserted through slot *j*, back of roller K. Attached to the customary device in a wagon-brake for setting the shoe against the face of the tire of the wheel, and for releasing it therefrom, is the usual and ordinary draw-rod, *n*, the forward end of which is attached to my lever through one of the perforations *l* or *m* in arm E. When the lever-arm B is thrown back, as shown in Fig. 1, the shoe is thrown out of engagement with the face of the tire on the wagon-wheel; but by throwing the lever-arm B and its attachment forward, as shown by the dotted lines in Fig. 1, the draw-rod *n* is forced forward and the shoe pressed backward against the face of the tire of the wheel. It will be observed that in this operation, after arm E passes forward, that part of it at *j* will traverse also downward on lever-arm B, so that the connection of draw-rod *n* in perforations *l* or *m* will gradually approach nearer to the pivotal point *d* of lever-arm B as said lever-arm is moved forward, thus continuously increasing the leverage of said lever-arm. It will also be observed that either one of the perforations *l* or *m* may be used for securing the forward end of draw-rod *n*, and if perforation *l* has been used for a considerable time for such purpose, and the shoe has become worn, the draw-rod *n* may be changed to perforation *m*, in which case the slack will be taken up and the shoe do more effective service. It will also be observed that by placing bolt *a* through perforation *h* or *i* the leverage of lever-arm B will be increased or diminished, accordingly as one or the other may be used.

When the operator desires to push back the draw-rod *n* to release the shoe from engagement with the tire of the wheel, he places his hand around the upper part of lever-arm B, and with his fingers presses the upper part of finger elbow-lever *e*, which disengages pawl D from the teeth or notches *c*, and then moves said lever-arm backward, the front end of pawl D moves forward against the arc of the plate until that part *c'*, which slightly raises the opposite end of pawl D causes its projection *g* to bind against the short parallel arm C, for the purpose hereinbefore explained.

The drawings represent the construction and arrangement considered best; but I do not

limit myself to the construction and arrangement here shown, because I have herein only represented but one of the many forms in which the invention may be embodied.

70

I do not claim as new in a wagon-brake a draw-rod connected with the lever-arm, and an arc, sector, or segmental bracket having notches or teeth on its lower edge to engage with a weighted or gravitating pawl on the pivoted lever-arm; but the important features of my invention are—

75

First. The addition of the projection *g* to the weighted pawl D, and the forward extension of the arc or segmental bracket C, not in a true circle, but on a tangent, as at *c'*. By these devices the lever-arm, when not in use to apply the brake, is held rigidly, so that it will not rattle or cause noise from the movement of the wagon. The front end of the pawl resting against that part of the arc at *c'* causes the projection *g* to bind against the lever-arm and rigidly hold it.

80

Second. The addition of the projection *g* to the weighted pawl, with the connecting-rod *f*, attached between said pawl and the elbow-lever *e*, limits the movement of elbow-lever *e*, by reason of projection *g* coming in contact with the lever-arm, thus avoiding danger of pinching the fingers when operating the lever-arm.

85

Third. The addition of the pivoted arm E, to swing or move in another circle than that of the lever-arm, its outer end encircling or partially encircling said lever-arm, so that movement of the lever-arm forward or back will also move arm E in a circle forward or back, and cause its outer end to traverse upward or downward on said lever-arm nearer to or farther from its fulcrum, and connecting the draw-rod to arm E, instead of to the lever-arm, gives increasing or diminishing leverage to the lever-arm to pull or push the draw-rod as the lever-arm is moved forward or backward.

90

What I claim as new, and desire to secure by Letters Patent, is—

95

1. In a lever for manipulating the draw-rod of a wagon-brake, the combination of a plate having a serrated arc, a lever-arm and pawl adapted to co-operate therewith, together with a projection on the pawl adapted to bind against a parallel arm connected to the lever-arm when the front end of the pawl, moved by the lever-arm, comes in contact with the arc of the plate forward of its serration, substantially as described.

100

2. In a lever for manipulating the draw-rod of a wagon-brake, the combination of a plate having a serrated arc, a lever-arm and pawl attached, adapted to engage with said serration, and to be disengaged by an elbow-lever upon the lever-arm, connected with said pawl by a rod, together with a projection upon said pawl, adapted to limit the movement of said pawl, connecting-rod, and elbow-lever by coming in contact with a parallel arm connected to the lever-arm, substantially as described.

105

110

115

120

125

130

3. In a lever attached to the side of a wagon-box for manipulating the draw-rod in a wagon-brake, the combination of a pivoted or hinged lever-arm, the arm E, pivoted at one end to the side of the wagon-box or its equivalent, the other end encircling or partially encircling the lever-arm, and a draw-rod connected to said arm near its point of attachment with said lever-

arm, whereby increased leverage is gained by the lever-arm to pull the draw-rod at a time to when the shoe of the brake rests against the tire of the wheel, substantially as described.
